UNITED STATES PATENT OFFICE.

GEORGE W. COPE, OF DETROIT, MICHIGAN, ASSIGNOR TO RALPH M. DYAR,
OF SAME PLACE.

DESIGN FOR A HEATING-STOVE.

SPECIFICATION forming part of Design No. 25,036, dated December 31, 1895.

Application filed October 29, 1895. Serial No. 567,321. Term of patent 7 years.

To all whom it may concern:

Be it known that I, GEORGE W. COPE, of Detroit, in the county of Wayne and State of Michigan, have invented a new and useful Design for Heating-Stoves, of which the following is a specification.

My invention consists in an improved design for stoves, adapted for use either as a wood or coal stove by putting in the proper grates.

The drawing is a perspective.

The body of the stove is substantially round, and is made up of plates A, which are substantially V-shaped, with the apex pointing outward.

The top B of the stove is arched and provided with ridges C, which meet the apexes of the plates A and fade away toward the crown of the arch of the ridges, and I place the bulk of the ornamentation of the stove upon the sides of the plates A near their apexes, leaving the bottom or groove of the plates comparatively plain, and follow out the same scheme of ornamentation on the top. In one of the ridges of the plates I leave an opening

adapted to be closed by a fire-door D, below which is an opening for a draft-door E, and below this there is an opening for an ash-door F.

G represents the legs of the stove.

The essential feature of my design is a stove having the outwardly-projecting V-shaped plates and the correspondingly ridged arched top by which the character of the stove is partly concealed—that is, the stove 35 gives the effect of a radiator rather than the effect of an independent stove. To carry this resemblance still farther, I present the scheme of ornamentation shown—that is, distributed principally at the top and bottom 40 of the plate A and upon the arched or crown-top B.

What I claim as my invention, and desire to secure by Letters Patent, is—

The design for a heating stove, herein 45 shown and described.

GEORGE W. COPE.
